REFRIGERATOR CONTROL

Charles S. Grimshaw, Erie, Pa., assignor to General Electric Company, a corporation of New York

Application December 28, 1956, Serial No. 203,166

16 Claims. (Cl. 200—83)

1

My invention relates to refrigerator controls and more particularly to such controls incorporating a defrost setting.

In many household refrigerators an evaporator used for cooling the food storage compartment is exposed to the air in the compartment and, since the evaporator operates substantially below the freezing temperature of water, moisture condenses on the evaporator and collects in the form of frost. In order to operate the refrigerating apparatus at a relatively high efficiency it is necessary to remove this frost from time to time. To accomplish this the refrigerator control may be provided with an arrangement for manually or automatically effecting an increased evaporator temperature at intervals. For normal operating conditions it is also desirable to provide for adjustment of the normal temperature setting so that the operating temperature of the evaporator can be properly varied under different operating conditions. However, it is usually desirable to establish some predetermined maximum temperature for the evaporator during the defrosting operation and it is desirable that the adjustment of the normal temperature setting not affect the defrosting temperature. In other words, it is advantageous to have the evaporator rise to the same maximum temperature during defrosting regardless of the particular normal temperature setting being employed at the time of defrosting. In many refrigerator controls an adjustable biasing spring is provided for securing the adjustable temperature during normal operating conditions and a second spring is employed for providing an additional opposing force which causes an increase in the evaporator temperature for defrosting, the biasing forces of the springs being added so that any variation in the normal temperature setting also affects the defrost temperature. By my arrangement two independent springs are provided so that one spring is effective during normal operating conditions and the other spring only is effective during defrosting conditions, and I have provided for the independent operation of these springs in a compact and simplified structure.

It is an object of my invention to provide a refrigerator control having a normal temperature control and a defrost control including an improved arrangement for rendering the defrost temperature independent of the normal temperature control.

It is another object of my invention to provide an arrangement for automatically initiating defrosting including an improved arrangement for

2

rendering the defrost temperature independent of any changes in the normal temperature setting.

Further objects and advantages of my invention will become apparent as the following description proceeds and the features of novelty which characterize my invention will be pointed out with particularity in the claims annexed to and forming part of this specification.

In carrying out the objects of my invention, a refrigerator control is employed which includes a conventional temperature-responsive element or bellows, a conventional adjustable spring opposing the bellows, and a conventional snap-acting switch. In lieu of a single pivoted arm which is 10 acted upon by the bellows and the opposing spring, I provide two parallel pivoted arms one of which is engaged by the spring and the other by the bellows. In addition, a second spring is 15 provided between the parallel arms opposing movement of the arms toward each other. During normal operation the two arms move as a unit and the operation of this switch is the same as if a single arm were employed. To accomplish defrosting a stop is arranged to function for 20 limiting the movement of the second arm and rendering the first spring ineffective. Under these conditions the second arm is moved by the bellows against the bias of the second spring only for ultimate actuation of the switch.

For a better understanding of my invention reference may be had to the accompanying drawings in which Fig. 1 illustrates a refrigerator control including an embodiment of my invention; Fig. 2 is a similar view of a modified form of my invention; and Fig. 3 is a view of a portion of Fig. 2 showing the control in a different position.

Referring to Fig. 1, there is shown a control which includes a housing 1 upon which is mounted a temperature-responsive element or bellows 2. The expansion and contraction of the bellows 2 is effected in response to the temperature registered by bulb (not shown) mounted on an evaporator (also not shown) and connected to the bellows by a tube 3. A switch 4 is provided 25 within the housing 1, the switch including a stationary contact 5 and a movable contact 6 for controlling the circuit of a refrigerating unit motor in a conventional manner.

A switch-actuating structure 7 is provided for 30 transmitting movement of the bellows 2 to effect opening and closing of the switch 4. The switch actuating structure 7 is biased for normal operating conditions by a spring 8. One end of the spring 8 engages a cup 9 and a threaded rod 10 35 is arranged in threaded engagement with the

tion, stopping operation of the refrigerating unit. Each time the bellows expands in the manner described and the arm 12 moves to the right, the pawl 43 also moves to the right to engage the next rearward tooth of the ratchet wheel 36. As the bellows then contracts during the other portion of the operating cycle, the arm 12 and the pawl 43 move to the left, thereby rotating the ratchet wheel 36 one tooth in a clockwise direction. This advances the stop 34 by the amount of one tooth in a clockwise direction.

After a predetermined number of cycles of operation of the refrigerating unit, or, in other words, after a predetermined number of complete operations of the control, the stop 34 is advanced to the dotted line position shown wherein it is aligned with the end 35 of the arm 24. As the bellows 2 thereafter expands during the warming up of the evaporator, the end 35 of the arm 24 encounters the stop 34, thereby limiting the movement of the arm 24. This also renders the spring 8 ineffective, since the spring 8 bears against the immobilized arm 24. Continued expansion of the bellows 2 thereafter moves the arm 12 against the bias of the spring 27, and the maximum temperature of the evaporator which is required to move the arm 12 to the overcenter position of the spring 20 and to close the switch 4 is determined by the bias of the spring 27, and is independent of the immobilized spring 8. The spring 27 is chosen so that it will require a greater pressure in bellows 2 to compress spring 27 than spring 8. Accordingly, under these conditions, the evaporator must rise to a predetermined temperature which exceeds the maximum temperature reached during normal operating conditions before the arm 12 is moved sufficiently to close the switch 4. The maximum evaporator temperature determined by the bias of the spring 27 is chosen so as to effect a complete melting of the frost from the evaporator, and is independent of the setting of the spring 8. At the end of the defrosting period, the ratchet wheel 36 is advanced one more tooth, thereby positioning the stop 34 beyond the end 35 of the arm 24 and returning the control to its normal operating condition.

Summarizing, it can be seen that by the arrangement shown the normal temperature conditions are determined by the setting of the knob 11 and the resultant bias of the spring 8, this spring alone opposing movement of the switch actuating structure during the normal operating conditions. On the other hand, during defrost conditions, the spring 8 is rendered ineffective because of the positioning of the stop 34 in line with the end 35 of the arm 24, and the maximum temperature is determined by the spring 27 independently of the spring 8. Thus, the normal operating temperatures of the evaporator can be varied by adjusting the knob 11, but such adjustment has no effect on the maximum temperature reached during the defrosting period. Although, for purposes of illustration, an automatic defrosting mechanism has been shown, it will be apparent that my invention could be carried out equally well by manually positioning a stop to limit the movement of the arm 24 for defrosting.

In Figs. 2 and 3, there is shown a modified form of my invention which also employs a stop effective under defrosting conditions for limiting the movement of the second arm so that the main spring is rendered ineffective and opposition to the expansion of the bellows is provided

by an independent defrosting spring. The modified form differs from that shown in Fig. 1 in that a rotatable cam is provided for varying the position of the movable switch arm in its open position and thereby varying the amount of expansion of the bellows necessary to effect a closing of the switch. The same numerals have been employed to designate corresponding parts in Figs. 2 and 3 and in Fig. 1.

Referring now to Figs. 2 and 3, the control there illustrated includes a movable arm 12' corresponding to the arm 12 of the control of Fig. 1 and a second arm 24' corresponding to the arm 24 of the form shown in Fig. 1. One end 24a of the arm 24' is received within an opening in the arm 12', the two arms 12' and 24' forming a unitary switch-actuating structure. As in the form previously described, an adjustable spring 8 bears against the arm 24' for opposing the bellows 2 during normal operation. The spring 27, adapted to be brought into play under defrost conditions, is arranged between the arms 12' and 24' and engages these arms. As illustrated, the spring 27 does not directly engage the arm 24' but it may be regarded as engaging the arm 24' since the dished member 30 and screw 31 may be considered part of the arm 24' and, moreover, these last-named parts may be omitted if adjustment of the spring is not desired. Relative movement of the arms 12' and 24' away from each other is limited by a stop 32' which is similar to the stop 32 of the form of Fig. 1.

The movable switch arm or member 18' which corresponds to the member 18 in the form of Fig. 1, includes a laterally extending leg 46 adapted to engage the periphery of a cam or rotatable member 47 which is supported on a bracket 47a mounted on the housing 1. The engagement of the leg 46 with the cam or disk 47 determines the position of the switch arm 18' and the movable contact 6 in the open position of the switch 4 and thereby determines the amount of movement of the arm 12' and hence the amount of expansion of the bellows 2 necessary to effect a closing of the switch. This is true since the closing of the switch is effected when the pivot point 17 of the U-shaped element 16 moves past the point 48 at which the end of the overcenter spring 20 is connected to the ear 22 of the arm 18'. Hence, variation in the position of the point 48, as determined by the engagement of the leg 46 with the cam 47, is effective to vary the temperature at which the switch 4 is closed. This characteristic is employed in the form of Figs. 2 and 3 for effecting defrosting.

The change in position of the switch arm 18' and the point 48 is achieved by forming the cam 47 with a recess 49 in the periphery thereof. To effect defrosting by requiring a greater expansion of the bellows 12' before closing of the switch 4, the cam 47 is rotated so as to position the recess 49 in line with the leg 46, as shown in Fig. 3. As can be seen by comparing Figs. 2 and 3, the distance between the pivot point 17 of the U-shaped element 16 and the point 48 in Fig. 3 is greater than in Fig. 2 and hence a greater movement of the arm 12' and of the bellows 2 is required before the spring 20 passes over center to cause closing of the switch 4. By way of illustration, the cam 47 has been shown as moved by a mechanism which includes an actuating pawl 52 and a retaining pawl 51 acting on a ratchet wheel 36 for rotating the cam 47; however, within the scope of this invention, any suitable arrangement, including manual rotation, may be

employed for rotating the cam 47 to position this cam for defrosting.

The variation in the required movement of the arm 12' is employed as a factor in rendering the spring 8 ineffective and the spring 27 effective under defrosting conditions. The arm 24' includes a portion or leg 52 which is aligned with a stop 53 formed on the housing 1. The relationship of the leg 52 to the stop 53 under normal operating conditions is such that the leg 52 falls just short of contacting the stop 53 by the time the point 17 passes the point 48 and the spring 20 shifts over center to close the switch 4. Hence, the arms 12' and 24' move as a unitary structure and the force opposing the expansion of the bellows 2 is provided by the spring 8. On the other hand when the cam 47 has been moved to the position as shown in Fig. 3, allowing the additional movement of the switch arm 18' in the open position of the switch 4, the additional travel of the arm 12' effects engagement of the leg 52 of the arm 24' with the stop 53, further movement of the arm 24' being thereafter prevented. As in the form previously described, this limiting of the movement of the arm 24' renders the spring 8 ineffective. The subsequent movement of the arm 12' required to move the spring 20 over center and close the switch 4 is thereafter a movement of the arm 12' relative to the arm 24' and hence is a movement opposed by the spring 27. Therefore, under the defrosting conditions, the movement of the bellows 2 to effect closing of the switch 4 is opposed by the spring 27 and is independent of the spring 8. Accordingly, the temperature at which the switch 4 closes is determined by the setting of the spring 27 and this maximum defrost temperature is independent of any changes in the compression of the spring 8 which may result from adjustments of a normal temperature setting by the knob 11.

Summarizing, with the arrangement shown in Figs. 2 and 3, the position of the cam 47 affects the position of the switch arm 18' and its leg 48 in the open position of the switch. This change in the position of the switch arm 18' varies the distance between the points 17 and 48, as indicated by a comparison of Figs. 2 and 3, and hence varies the distance which the arm 12' must be moved by the expansion of the bellows in order to effect an over center movement of the spring 20 and a closing of the switch 4. Moreover, the amount of travel required by the arm 12' under normal conditions, as illustrated in Fig. 2, to close the switch 4 is such that the leg 52 of the arm 24' does not engage the stop 53. On the other hand, under the defrost conditions illustrated in Fig. 3, the stop 53 is effective to engage the leg 52 because of the increased travel of the arm 12' and arm 24', rendering the spring 8 ineffective, and introducing the spring 27 as the sole force opposing the expansion of the bellows because of the relative movement thereafter of the arms 12' and 24'.

While I have shown and described specific embodiments of my invention, I do not desire my invention to be limited to the particular constructions shown and described and I intend by the appended claims to cover all modifications within the spirit and scope of my invention.

What I claim as new and desire to secure by Letters Patent of the United States is:

1. A refrigerator control including a first movable arm, a temperature-responsive element for moving said first arm, a switch actuated by said arm at a predetermined temperature, a second

movable arm, means engaging said second arm for opposing said temperature-responsive element, a spring between said two arms and engaging said arms for normally maintaining said arms in spaced relationship, and a stop arranged to function for limiting the movement of said second arm whereby said temperature-responsive element moves said first arm relative to said second arm against the bias of said spring effecting defrosting.

2. A refrigerator control including a first movable arm, a temperature-responsive element for moving said first arm, a switch actuated by said arm at a predetermined temperature, a second movable arm, means engaging said second arm for opposing said temperature-responsive element, said means being adjustable for varying the temperature at which said switch is actuated, a spring between said two arms and engaging said arms for normally maintaining said arms in spaced relationship, and a stop arranged to function for limiting the movement of said second arm whereby said temperature-responsive element moves said first arm relative to said second arm against the bias of said spring for effecting defrosting.

3. A refrigerator control including a movable arm, a temperature-responsive element for moving said arm, a switch actuated by said arm at a predetermined temperature, a second movable arm, means engaging said second arm for opposing said temperature-responsive element, a spring between said two arms and engaging said arms for normally maintaining said arms in spaced relationship, and a stop movable to a position in the path of said second arm for limiting the movement thereof whereby said temperature-responsive element moves said first arm relative to said second arm against the bias of said spring for effecting defrosting.

4. A refrigerator control including a movable arm, a temperature-responsive element for moving said arm, a switch actuated by said arm at a predetermined temperature, a second movable arm, means engaging said second arm for opposing said temperature-responsive element, said means being adjustable for varying the temperature at which said switch is actuated, a spring between said two arms and engaging said arms for normally maintaining said arms in spaced relationship, and a stop movable to a position in the path of said second arm for limiting the movement thereof whereby said temperature-responsive element moves said first arm relative to said second arm against the bias of said spring for effecting defrosting.

5. A refrigerator control including two movable arms, said arms being movable as a unit during normal operation, a temperature-responsive element for moving said arms, a switch actuated by the movement of one of said arms, means engaging the other of said arms for opposing movement of said arms, said means being adjustable for varying the temperature at which said switch is actuated, means for limiting the movement of said other of said arms under predetermined conditions, and a spring for opposing relative movement of said arms whereby movement of said one of said arms for actuating said switch is opposed by said spring under said predetermined conditions.

6. A refrigerator control comprising a switch-actuating structure, a switch actuated thereby, said switch-actuating structure including two parallel arms, one of said arms including a por-

tion for actuating said switch, a temperature-responsive element engaging said one of said arms for effecting movement of said arms, an adjustable first spring engaging the other of said arms for biasing said switch-actuating structure, a second spring disposed between said arms and engaging said arms for biasing said arms against relative movement, and a stop for engaging said other of said arms under predetermined conditions for limiting movement of said other of said arms and rendering said first spring ineffective whereby the movement of said one of said arms for actuating said switch under said predetermined conditions is opposed by the bias of said second spring only.

7. A refrigerator control comprising a switch and mechanism for actuating said switch, said mechanism including a first pivoted arm connected to said switch, a second parallel pivoted arm, a first spring between said arms and engaging said arms for biasing said arms against relative movement toward each other, a temperature-responsive element engaging said first arm for effecting movement thereof, a second spring engaging said second arm for biasing said arms during normal operation, and a stop for engaging said second arm for limiting movement thereof whereby said second spring is rendered ineffective and subsequent movement of said first arm is opposed only by said first spring.

8. A refrigerator control comprising a switch and mechanism for actuating said switch, said mechanism including a first pivoted arm connected to said switch, a second parallel pivoted arm, a first spring between said arms and engaging said arms for biasing said arms against relative movement toward each other, a temperature-responsive element engaging said first arm for effecting movement thereof, a second spring engaging said second arm for biasing said arms during normal operation, means for adjusting said second spring to vary the bias exerted thereby, and a stop for engaging said second arm to limit movement thereof whereby said second spring is rendered ineffective and subsequent movement of said first arm is opposed only by said first spring.

9. A refrigerator control comprising a switch and mechanism for actuating said switch, said mechanism including a first pivoted arm connected to said switch, a second parallel pivoted arm, a first spring between said arms and engaging said arms for biasing said arms against relative movement toward each other, a temperature-responsive element engaging said first arm for effecting movement thereof, a second spring engaging said second arm for biasing said arms during normal operation, a rotatable member, said rotatable member having a projection thereon for engaging said second arm, and means for rotating said member to position said projection in line with said second arm for limiting the movement of said second arm whereby said second spring is rendered ineffective and subsequent movement of said first arm is opposed only by said first spring.

10. A refrigerator control comprising a switch and mechanism for actuating said switch, said mechanism including a first pivoted arm connected to said switch, a second arm pivoted on said first arm and extending parallel thereto, a first spring between said arms and engaging said arms for biasing said arms against relative movement toward each other, a temperature-responsive element engaging said first arm for effecting

movement thereof, a second spring engaging said second arm for biasing said arms during normal operation, and a stop for engaging said second arm to limit movement thereof whereby said second spring is rendered ineffective and subsequent movement of said first arm is opposed only by said first spring.

11. A refrigerator control comprising a switch and mechanism for actuating said switch, said mechanism including a first pivoted arm connected to said switch, a second parallel pivoted arm, a first spring between said arms and engaging said arms for biasing said arms against relative movement toward each other, a stop for limiting the movement of said arms away from each other, a temperature-responsive element engaging said first arm for effecting movement thereof, a second spring engaging said second arm for biasing said arms during normal operation, and a second stop for engaging said second arm to limit movement thereof whereby said second spring is rendered ineffective and subsequent movement of said first arm is opposed only by said first spring.

12. A refrigerator control comprising a switch and mechanism for actuating said switch, said mechanism including a first movable arm, a second movable arm, a first spring between said arms and engaging said arms for biasing said arms against relative movement toward each other, a temperature-responsive element engaging said first arm for effecting movement thereof, a second spring engaging said second arm for biasing said arms during normal operation, a first stop for engaging said second arm to limit movement thereof whereby said second spring is rendered ineffective and subsequent movement of said first arm is opposed only by said first spring, a switch member having a movable contact thereon, an overcenter spring between said first arm and said switch member, and a second stop for normally limiting movement of said switch member in the open position of said switch whereby said overcenter spring is moved over center to close said switch before engagement of said first stop by said second arm, said second stop being movable to afford increased movement of said switch member in its open position during defrosting whereby increased movement of said first arm is required for moving said overcenter spring over center to close said switch, said increased movement of said first arm first effecting engagement of said first stop by said second arm and thereafter being opposed only by said first spring.

13. A refrigerator control comprising a switch and mechanism for actuating said switch, said mechanism including two movable arms, said arms being movable as a unit during normal operation, a temperature-responsive element for moving said arms, a switch actuated by movement of one of said arms, means engaging the other of said arms for opposing movement of said arms, said means being adjustable for varying the temperature at which said switch is actuated, a first stop for limiting the movement of said other of said arms under predetermined conditions, a first spring for opposing relative movement of said arms whereby movement of said one of said arms for actuating said switch is opposed by said spring under said predetermined conditions, said switch including a switch member having a movable contact thereon, an overcenter spring between said one of said arms and said switch member, a second stop for normally limiting

movement of said switch member in the open position of said switch whereby said over-center spring is moved over center to close said switch before engagement of said first stop by said other of said arms, said second stop being movable to afford increased movement of said switch member in its open position during defrosting whereby increased movement of said one of said arms is required for moving said overcenter spring over center to close said switch, said increased movement of said one of said arms first effecting engagement of said first stop by said other of said arms and thereafter being opposed only by said first spring.

14. A refrigerator control comprising a switch and mechanism for actuating said switch, said mechanism including a first movable arm, a second movable arm, a first spring between said arms and engaging said arms for biasing said arms against relative movement toward each other, a temperature-responsive element engaging said first arm for effecting movement thereof, a second spring engaging said second arm for biasing said arms during normal operation, a stop for engaging said second arm to limit movement thereof whereby said second spring is rendered ineffective and subsequent movement of said first arm is opposed only by said first spring, a switch member having a movable contact thereon, an overcenter spring between said first arm and said switch member, a cam adapted to occupy one position for normally limiting movement of said switch member in the open position of said switch whereby said overcenter spring is moved over center to close said switch before engagement of said stop by said second arm, said cam being movable to a second position for affording increased movement of said switch member in its open position during defrosting whereby increased movement of said first arm is required for moving said overcenter spring over center to close said switch, said increased movement of said first arm first effecting engagement of said stop by said second arm and thereafter being opposed only by said first spring.

15. A refrigerator control comprising a switch and mechanism for actuating said switch, said mechanism including a first movable arm, a second movable arm, a first spring between said arms and engaging said arms for biasing said arms against relative movement toward each other, a temperature-responsive element engaging said first arm for effecting movement thereof, a second spring engaging said second arm for biasing said arms during normal operation, a stop for engaging said second arm to limit movement thereof whereby said second spring is rendered ineffective and subsequent movement of said first arm is opposed only by said first spring, a switch member having a movable contact thereon, an overcenter spring between said first arm

and said switch member, a rotatable disk, the periphery of said disc being engaged by said switch arm in the open position of said switch for normally limiting movement of said switch arm whereby said overcenter spring is moved over center to close said switch before engagement of said stop by said second arm, said disk having a recess in the periphery thereof, said disk being movable to a position wherein said recess is aligned with said switch member to afford increased movement of said switch member in its open position during defrosting whereby increased movement of said first arm is required for moving said overcenter spring over center to close said switch, said increased movement of said first arm first effecting engagement of said stop by said second arm and thereafter being opposed only by said first spring.

16. A refrigerator control comprising a switch and mechanism for actuating said switch, said mechanism including a first movable arm, a second movable arm, a first spring between said arms and engaging said arms for biasing said arms against relative movement toward each other, a temperature-responsive element engaging said first arm for effecting movement thereof, a second spring engaging said second arm for biasing said arms during normal operation, a stop for engaging said second arm to limit movement thereof whereby said second spring is rendered ineffective and subsequent movement of said first arm is opposed only by said first spring, a switch member having a movable contact thereon, an overcenter spring between said first arm and said switch member, a rotatable disk, the periphery of said disk being engaged by said switch arm in the open position of said switch for normally limiting movement of said switch arm whereby said overcenter spring is moved over center to close said switch before engagement of said stop by said second arm, said disk having a recess in the periphery thereof, means for rotating said disk to a position wherein said recess is aligned with said switch member to afford increased movement of said switch member in its open position during defrosting whereby increased movement of said first arm is required for moving said overcenter spring over center to close said switch, said increased movement of said first arm first effecting engagement of said stop by said second arm and thereafter being opposed only by said first spring.
